UNITED STATES PATENT OFFICE.

ALBERT LATHAM, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE-SEWING MACHINE.

1,341,061.

Specification of Letters Patent. Patented May 25, 1920.

Application filed December 26, 1912, Serial No. 738,674. Renewed September 26, 1917. Serial No. 193,389.

To all whom it may concern:

Be it known that I, ALBERT LATHAM, a citizen of the United States, residing at Beverly, in the county of Essex and State of Massachusetts, have invented certain new and useful Improvements in Shoe-Sewing Machines; and I do hereby declare the following to be a full, clear, and exact description of the invention, such as will enable others skilled in the art to which it appertains to make and use the same.

The invention relates to sewing machines such as are used in the manufacture of boots and shoes, and more particularly to devices and mechanisms for facilitating the removal of a completed shoe from the machine and the starting of the seam at the beginning of the sewing operation on the succeeding shoe.

The object of the invention is to provide novel and improved mechanism for automatically reversing the machine to free the thread from the needle, and for automatically cutting the welt at the completion of the sewing of a shoe, and for holding the welt end at the beginning of the seam of the next succeeding shoe, and to further improve various mechanisms of the machine.

To these ends the invention consists in the features of construction and combinations of parts hereinafter described and referred to in the claims.

The various features of the invention will be readily understood from an inspection of the accompanying drawings and the following detailed description of the machine illustrated therein.

In the drawings, Figure 1 is a side elevation of a welt and turn sewing machine embodying the invention in its preferred form; Fig. 2 is a similar view showing the parts at the end of the cam shaft on a larger scale; Fig. 3 is a front elevation of the parts carried on the head of the machine; Fig. 4 is a vertical sectional view on line 4—4, Fig. 2; Fig. 5 is a horizontal sectional view on line 5—5, Fig. 3; Fig. 6 is a vertical sectional view on line 6—6, Fig. 3; Fig. 7 is a vertical sectional view on line 7—7, Fig. 3; Fig. 8 is a vertical sectional view on line 8—8, Fig.

5; Fig. 9 is a detail elevation looking toward the left in Fig. 4, a part of the frame being broken away to show the parts behind it; Fig. 10 is a horizontal sectional view on line 10—10, Fig. 8; Fig. 11 is a horizontal sectional view on line 11—11, Fig. 6; Fig. 12 is a detail plan view partly in section showing the clutches for operating the mechanism which reverses the cam shaft and for operating the welt cutting and holding device; Fig. 13 is a vertical sectional view on line 13—13, Fig. 12; Fig. 14 is a vertical sectional view on line 14—14, Fig. 11; Fig. 15 is a vertical sectional view on line 15—15, Fig. 11; Fig. 16 is a sectional view on line 16—16, Fig. 4; Fig. 17 is a detail elevation showing the whole elevation of the stopping mechanism shown in Fig. 16, the brake carrying disk being removed to show the parts behind it; Fig. 18 is a sectional view on line 18—18, Fig. 17; Fig. 19 is a vertical sectional view on line 19—19, Fig. 8; Fig. 20 is a horizontal sectional view on line 20—20, Fig. 19; Fig. 21 is a vertical sectional view through the brake applying cylinder and piston; Figs. 22, 23 and 24 are sectional elevations showing parts of the mechanism for moving the welt holding grippers with the shoe during the sewing of one or more stitches; Fig. 25 is a detail side elevation showing the welt holding grippers and cutter; Fig. 26 is a plan view of the parts shown in Fig. 25; Fig. 27 is a side elevation of the parts shown in Fig. 25; showing the other side of the parts; Fig. 28 is a sectional elevation similar to Fig. 27, showing the parts in a different position; Fig. 29 is a sectional view on line 29—29, Fig. 26; Figs. 30 and 31 are details of the thread cutting and holding device; and Fig. 32 is a vertical sectional view through the axis of the driving clutches which are mounted in the base of the machine.

The invention is shown as embodied in a welt sewing machine having the construction and mode of operation of the machine illustrated and described in the application of Andrew Eppler, Serial No. 447,542, filed August 8, 1908, on which Patent No.

1,108,560 was granted August 25, 1914, except so far as the construction of the machine has been modified in applying the invention thereto.

5 The machine is driven through a treadle controlled clutch arranged in the base of the machine, and is provided with mechanism which upon the release of the treadle arrests the forward motion of the cam shaft and 10 then turns it back to retract the needle while its hook is empty, and brings the machine to rest with the parts in position for the removal of the shoe. Devices are also provided for automatically severing the 15 welt after the machine has been brought to rest, and for holding the end of the welt in position for attaching it to the succeeding shoe. These devices move with the shoe during the sewing of one or more stitches, 20 and are then automatically disengaged from the welt and move out of the way during the completion of the sewing operation. A device is also provided for severing the thread and for holding its free end under 25 tension during the sewing of one or more stitches at the beginning of the seam.

In general the mode of operation of these mechanisms and devices is as follows: When the controlling lever is released the main 30 driving clutch is thrown out, a slow speed driving clutch is thrown in, and a brake is applied to the hand wheel on the end of the cam shaft of the machine, and is immediately released. The temporary application 35 of the brake quickly reduces the speed of the cam shaft, and leaves it under driving control of the slow speed clutch. The release of the treadle also causes a stop bar to engage and stop a brake disk carried on 40 the cam shaft, and the continued rotation of the cam shaft applies the brake and stops the forward rotation of the shaft. As the cam shaft completes its forward rotation it throws into operation a one revolution 45 clutch, the rotation of which first disengages a driving clutch on the end of the cam shaft, thus freeing the shaft from the slow speed driving mechanism, and then actuates the reversing mechanism to turn the cam shaft back to stopping position. After the 50 cam shaft has been turned back, the final movement of the reversing mechanism trips a clutch which operates the welt cutting and holding device. This clutch makes a partial revolution to bring the welt cutting and holding devices into position to sever and hold the welt, and then stops. At the 55 beginning of the next sewing operation the clutch is automatically tripped after one or two stitches have been formed, and completes its revolution to disengage and withdraw the welt holding devices. The depression 60 of the treadle in starting the machine reengages the driving clutch on the end of the cam shaft, and the clutch is latched in

engagement until it is again thrown out, as above described.

The sewing machine shown is provided with the curved hook needle 1, the looper 2, the thread finger 3, the welt guide 4, the 70 back gage 5, the feed point 6, and the channel guide 7, all of which are operated through suitable connections by cams carried by the cam shaft 8. As is usual in this type of machine the cam shaft makes one 75 revolution for each cycle of operations performed by the stitch forming and work feeding devices.

During the sewing the machine is driven through a belt pulley 9 carrying one member 10 of a driving clutch, the other member 11 of which is formed on a hand wheel 12 secured to the cam shaft 8. The pulley 9 is mounted to turn and slide freely on the hub of the hand wheel 12, and during the 85 sewing is forced toward the hand wheel by a lever 13, the upper end of which carries a screw 14 engaging a bearing point 15 secured to the pulley. A felt lubricating sleeve 16 surrounds the screw and bearing point, as indicated in Fig. 4. The lever 13 is operated to engage and disengage the clutch members between the driving pulley 9 and hand wheel 12 by mechanism which 90 will be described later.

The pulley 9 is connected by a driving belt 17 with a pulley 18 secured to a shaft 19 mounted in the base of the machine. The shaft 19 is connected through bevel gears 20 with a hollow driving shaft 21 100 which carries a driving clutch 22 (Figs. 1 and 32). The clutch 22 is mounted to slide on the shaft 21, and is connected to turn therewith by a pin 23 which passes through the hub of the clutch, through slots formed in the shaft, and through a clutch shifting rod 24 mounted within the shaft. The clutch 22 is provided with a main driving clutch member 25 arranged to engage a clutch member 26 formed on the high speed 110 driving pulley 27. The clutch is also provided with a clutch member 28 adapted to engage a clutch member 29 formed on the low speed driving pulley 30. The clutch is forced in a direction to engage the members 115 of the low speed clutch by a spring 31 acting on the rod 24, and is moved in a direction to engage the high speed clutch members by a wedge block 32 adapted to engage inclined surfaces formed on a sleeve 33. 120 The sleeve 33 is mounted on a stationary bearing sleeve 34, and is arranged to engage thrust collars 35 interposed between the sleeve and a collar 36 secured to the rod 24. The wedge block 32 is connected by a link 125 37 with a lever 38 arranged to be engaged by a screw 39 carried by a treadle 40. The lever 38 is moved in a direction to raise the wedge block 32 by a spring 41, and the upward movement of the lever and block is 130

limited by a stop screw 42. When the treadle is depressed, the clutch members 25 and 26 are engaged, and the machine is driven from a high speed main driving pulley 27, the speed of the machine being regulated by varying the pressure upon the treadle in the usual manner. When the treadle is released the main driving clutch is disengaged, and the clutch members 28 and 29 are engaged, so that the machine is driven from the slow speed pulley 30.

When the treadle is released to disengage the main driving clutch and throw in the slow speed driving clutch, a friction brake 15 is momentarily applied to the hand wheel 12 to reduce the speed of the cam shaft through the following mechanism. The treadle 40 is connected by a link 43 with an arm 44 secured to a rock shaft 45. The rock shaft is moved in a direction to raise the treadle by a spring 46 connected to an arm 47 on the shaft. One end of the shaft carries an arm 48 which is connected to the lower end of a link 49, the upper end of which is connected to the lower end of a vertically sliding rod 50 (Figs. 1 and 2). The upper end of the link is provided with a rearwardly extending arm 51 pivotally connected to a brake cylinder 52. The cylinder surrounds and is free to slide on a piston 53 carried by the lower end of a piston rod 54 which passes through a stuffing box in the upper end of the cylinder and is pivotally connected at its upper end with a 35 brake carrying arm 55 (Figs. 2 and 21). The brake carrying arm is pivoted at 56, and carries a brake shoe 57 arranged to engage the rim of the hand wheel 12. The cylinder 52 is provided with a port 58 near its lower 40 end, a port 59 about midway of its length, and a port 60 at its upper end. The opening through the ports 58 and 59 may be adjusted by the screws 61 and 62, and the opening through the port 60 may be adjusted 45 by the thumb screw 63. The piston is provided with ports 64, the lower ends of which are closed by a spring supported valve 65. The ports 58, 59 and 60 communicate with a passage 66 along the side of the cylinder, and the ports 58 and 59 are so adjusted that there is free communication between opposite sides of the piston when these 50 ports are open, while the port 60 is so adjusted that it forms a restricted vent for the passage of the liquid from the cylinder. The cylinder is filled with oil or other suitable liquid. When the treadle is depressed the cylinder 52 is drawn down, so that the piston 53 is at the upper end of the cylinder. When the cylinder is in this position the piston 53 covers the port 59, and the only communication from one side of the piston to the other is through the restricted port 60. When the treadle is released the 55 cylinder is raised and acts to force the brake

against the hand wheel. The upward pressure on the cylinder causes the liquid below the piston to gradually flow through the port 60 to the upper end of the cylinder, so that the cylinder gradually rises. The upward movement of the cylinder finally carries the port 59 above the piston, so that there is free communication from one side of the piston to the other, with a resulting release of the pressure on the brake carrying arm. The piston and cylinder therefore act to apply the brake when the treadle is released, and the pressure on the brake is immediately relieved, so that it does not interfere with the movement of the cam shaft 75 under the influence of the slow forward drive or reversing mechanism. When the cylinder is drawn down by the depression of the treadle, the liquid above the cylinder passes freely to the lower side of the piston through 80 the ports 64, the valve 65 yielding to allow the passage of the liquid in this direction, but preventing the passage of the liquid in the opposite direction when the cylinder rises. The interval during which the brake 90 is applied may be regulated by adjusting the thumb screw 63 which controls the opening through the port 60.

The release of the treadle also throws into operation the mechanism for stopping and reversing the cam shaft. These mechanisms are controlled through devices operated by the upward movement of the rod 50 when the treadle is released. These devices comprise a cam shaft 67 carrying cams for controlling the stopping and reversing mechanisms, and operated through the rod 50 and connected treadle by a rack 68 formed on the rod and engaging a pinion 69 secured to the shaft. The upward movement of the rod 100 50 when the treadle is released rocks the cam shaft 67 to throw the stopping mechanism into operation, and then the upward movement of the rod and treadle is arrested by the engagement of the upper end of the rod 105 with the under side of a slide 70 which at this time is in position over the end of the rod. As the cam shaft 8 completes its forward movement, the slide 70 is withdrawn, so that the rod 50 completes its upward movement and rocks the cam shaft 67 to throw the reversing mechanism into operation. Since the brake cylinder 52 is connected with the rod 50, the cylinder and piston not only act to apply the brake when 110 the treadle is released, but also retard the upward movement of the rod 50 and the throwing into operation of the stopping mechanism until the brake has acted to slow down the cam shaft 8 of the machine to the 115 speed of the slow speed driving mechanism. This insures the stopping of the forward motion of the cam shaft without undue shock or jar, and a uniform and reliable action of the stopping mechanism.

The stopping mechanism comprises a disk 71 loosely mounted on the hub of the hand wheel 12, and carrying the semicircular brake shoes 72 which are arranged to engage 5 the inner surface of a cylindrical flange 73 on the hand wheel. The brake shoes are pivotally connected to the disk by a pivot screw 74, and are provided at their free ends with devices for forcing them into engagement 10 with the flange 73. These devices comprise a roll 75 mounted in the end of one of the shoes, and arranged to bear against a block 76 pivoted to the end of the other shoe and provided with a roll 77. The roll 77 is arranged 15 to travel on the surface of a cam sleeve 78 which is secured to the hand wheel, and is provided with a cam surface 79 for coöperating with the roll 77 to spread the brake shoes and stop the rotation of the 20 hand wheel and connected cam shaft. The brake disk 71 is connected with the sleeve 78 by a spring 80 which normally holds the disk in position with the head of the screw 74 against a stop shoulder 81 formed on a lug which projects from the sleeve 78. During 25 the normal running of the machine the brake disk 71 rotates with the hand wheel and cam shaft in the direction of the arrows, Figs. 16 and 17. When the cam shaft 30 67 is rocked upon the release of the treadle a stop bar 82 which has been held in retracted position by a cam 83 on the shaft 67 is released by the cam, so that it is forced upward by the spring pressed pin 84 which 35 engages the lower end of the bar. The bar now rides along the periphery of the disk 71 until it is engaged by a stop shoulder 85 on the disk, when it rises into the notch, one side of which is formed by the shoulder 85, 40 and arrests the rotation of the disk 71. The cam shaft 8 continues to rotate after the disk has been stopped, until the roll 77 on the brake shoe rides up the cam surface 79. The engagement of the cam 79 on the roll 77 first 45 expands the brake shoes to overcome the inertia of the cam shaft, and then acts as a positive stop for arresting the forward movement of the cam shaft.

The upward movement of the stop bar 50 82 into the notch in the brake disk 71 not only arrests the movement of the disk to stop the cam shaft of the machine, but also brings the devices for withdrawing the slide 70 into position to be actuated by the final forward movement of the cam shaft. The devices for operating the slide 70 comprise a lever 86 pivotally connected to a vertically movable slide 87 by a pivot screw 88 which also connects the slide with the bar 82, as 55 shown in Fig. 4. The lower end of the lever 86 engages a vertical slot formed in the slide 70, and the upper end of the lever carries a pivoted finger 89. The finger is provided with a slot 90, one end of which 60 is normally held against a stop pin 91 by a

spring 92. When the stop bar 82 rises into the notch in the brake disk, the finger 89 is moved up into the groove 93 formed in a sleeve 94 which is secured to the hub of the hand wheel 12. This brings the finger into the path of a shoulder 95 which projects across the groove and is so arranged that it engages the finger as the cam shaft 8 of the machine completes its forward movement. When the shoulder engages the finger, it rocks the lever 86 to withdraw the slide 70, and allow the rod 50 to complete its upward movement, and thus further rock the cam shaft 67. The finger 89 is free to swing idly about its pivot on the lever 86 when struck by the shoulder 95 during the reverse movement of the cam shaft. The mechanism which is thrown into operation by the final rocking movement of the cam shaft 67 to turn the cam shaft of the machine back to 85 stopping position comprises a pawl carrying segment 96 mounted to turn about the cam shaft 8, and provided with a radially extending arm 97 carrying a pawl 98 which is arranged to engage a tooth 99 formed on a flange 100 of the sleeve 94 (Figs. 4, 6 and 7). The pawl is drawn toward the flange 100 by a spring 101, and is normally held out of engagement with the flange by a stationary cam 102 which engages the tail of the pawl 95 when the pawl carrying arm 97 is in its normal retracted position indicated in Figs. 6 and 7. The pawl carrying segment 96 is provided with gear teeth engaged by teeth formed on a segment 103 which is actuated 100 through a crank pin 104 carried by a disk 105 and connected with the segment 103 by a link 106. The disk is normally stationary, and is given a single revolution to advance and retract the reversing pawl after the advance 105 movement of the cam shaft has been arrested. The disk also carries a cam 107 which acts at the beginning of the rotation of the disk to disengage the driving pulley 9 from the hand wheel 12 so that the cam shaft is free 110 to be moved back by the reversing pawl. The devices through which this is effected comprise a rock shaft 108 carrying an arm 109 arranged to be engaged and operated by the cam 107. The rock shaft 108 also carries a latch arm 110 which passes between the lower end of the clutch controlling lever 13 and a fixed surface 111 on the supporting frame work of the machine (Figs. 2, 3, 4 and 5). The lever 110 is provided with a 115 projecting lug 112 adapted to engage the end of a screw 113 carried by the lever 13. When the treadle of the machine is depressed in starting the machine, the lever 13 is actuated to engage the clutch members between the driving pulley 9 and the hand wheel 12 by a cam 114 secured on the end of the cam shaft 67, and provided with cam surfaces adapted to engage segmental rolls 120 115 carried by the lever 13. The rolls are 130

yieldingly held in normal position by the latch springs 116, and are so arranged that when the cam shaft 67 is rotated by the depression of the treadle the circular periphery of the rolls will ride against the swells on the cam 114 so that the cam will force the lower end of the lever 13 toward the left in Fig. 4 to engage the clutch members 10 and 11. When this occurs the latch arm 110 is raised by its spring 117 so that the lug 112 passes in front of the screw 113, thus latching the clutch members in engagement. When the cam shaft 67 is rocked in the opposite direction upon the release of the treadle, the segmental roll 115 will yield to allow the swells on the cam 114 to pass freely by the rolls, so that the cam and rolls will not interfere with the free rocking of the shaft in this direction.

When the cam 107 on the disk 105 engages the arm 109, it rocks the shaft 108 and swings the latching arm 110 downward, thus releasing the lever 13 so that it is operated by a spring 118 to disengage the clutch members 10 and 11. After the clutch members have thus disengaged, the continued rotation of the disk 105 advances the reversing pawl 98 so that it rides from under the cam 102 and engages the tooth 99 and turns the cam shaft back with a gradually accelerated and then gradually retarded motion into the position indicated in Figs. 6 and 7. When the reversing pawl starts forward, a cam 119 on the pawl carrying arm 97 rides from under a roll 120 carried on a pivot on a stop pawl 121, and allows the stop pawl to drop into engagement with the flange 122 of the sleeve 94. As the reversing pawl 98 completes its forward movement, the stop pawl 121 engages a shoulder 123 on the flange 122 and drops into a notch 124, thus accurately positioning the cam shaft 8 of the machine, and preventing any overthrow by the reversing pawl. As the pawl carrying segment 45 completes its return movement into its normal position indicated in Figs. 6 and 7, the tail of the pawl rides under the cam 102, thus disengaging the pawl from the flange 100, and the cam 119 rides under the roll 120, thus disengaging the stop pawl 121 from the flange 122.

The mechanism for actuating the disk 105 is shown in Figs. 11 to 14. The disk is formed on the end of a hollow shaft or sleeve 125 which surrounds a shaft 126, and the disk is held within the casing 127 by a retaining plate 128 engaging an annular flange 129 on the outer periphery of the disk. A clutch member 130 is connected to rotate with the disk by pins 131 which permit the clutch member to move axially of the disk. The clutch member is provided on one end with clutch teeth adapted to engage corresponding clutch teeth formed on the opposing face of a continuously rotating gear

132. The clutch member is forced toward the gear by springs 133, and its movement toward and from the gear is controlled by a clutch controlling sleeve 134 which surrounds the clutch member and is interposed between the disk 105 and gear 132. The controlling sleeve is provided with inclined or spiral ribs 135 engaging corresponding grooves in the clutch member. When the controlling sleeve is free to rotate, the springs 133 will force the clutch member 130 into engagement with the gear 132, so that the clutch member, disk and controlling sleeve will rotate in unison. If the rotation of the controlling sleeve is arrested, however, the inclined ribs 135 will act to draw the clutch member 130 away from the gear 132, thus disengaging the clutch member from the gear and arresting the rotation of the clutch member and disk 105. The controller sleeve 134 is normally held against rotation by a controller slide 136 provided at its rear end with a projecting tooth 137 arranged to engage a stop shoulder 138 on the sleeve 134. The slide is forced toward the controller sleeve by a spring 139 interposed between a bushing 140 and the head of a sleeve 141 which is threaded on a screw 142 carried by a lug 143 which depends from the forward end of the slide (Fig. 14). The slide is withdrawn to throw the actuating clutch for the reversing mechanism into operation by the final rocking movement of the cam shaft 67, which takes place as above described as the main cam shaft 8 completes its forward movement. The devices for withdrawing the slide comprise a cam 144 projecting from a sleeve 145 which is mounted on the inner end of the cam shaft 67. The sleeve 145 is provided with lugs 146 adapted to be engaged by lugs 147 formed on a collar 148 which is secured to the shaft 67. The cam 144 is arranged to co-operate with a dog 149 pivoted to the outer end of the slide 136, and held yieldingly in normal position by a flat spring 150 which engages the flat end of the dog (Figs. 11 and 14). The movement of the dog on its pivot is limited by a pin 151 which projects from the side of the dog into a slot formed in the slide 136. When the cam shaft 67 is rocked by the depression of the treadle in starting the machine, the lugs 147 engage the lugs 146 and rock the cam sleeve 145 in a direction to carry the cam 144 down below the end of the dog 149, the dog yielding to allow the cam to pass, and then springing back into normal position so that its inner end lies above the cam 144. The lugs 146 and 147 are so formed that there is a certain amount of lost motion between them, and when the treadle is released in stopping the machine the first rocking movement imparted to the cam shaft 67, as above described, merely takes up this lost motion, so that the cam 130

144 remains below the end of the dog 149. When the final rocking movement is imparted to the shaft 67 at the end of the forward movement of the cam shaft 8 of the machine, 5 the cam 144 rides up against the end of the dog 149, and after the pin 151 on the dog has engaged the upper end of the slot in the bar 136, the continued movement of the cam 144 forces the slide 136 toward the right in Fig. 14, withdrawing the tooth 137 from engagement with the shoulder on the controller sleeve 134, and thus throwing the clutch for operating the reversing mechanism into 10 operation. The disk 105 is now driven 15 through a single revolution as above described, and then the clutch is disengaged by the engagement of the shoulder 138 with the tooth 137. As the cam 144 passes the point of the dog 149, the spring 150 forces the dog downward slightly, so that 20 the point of the dog is freed from the point of the cam, and the slide 136 is free to move inward into a position to engage the shoulder 138. In order to insure the disengagement 25 of the end of the dog from the end of the cam, a cam 152 is formed on the controller sleeve 134, and is arranged to engage the inner end of the slide 136 and force the slide toward the right in Fig. 14 beyond the position to which it is forced by the cam 144. 30 This frees the end of the dog from the cam, so that it may snap back into position to pass under the cam after the cam 152 has passed beyond the end of the slide 136. As 35 the clutch member and disk 105 complete their revolution, and the clutch member is thrown out, a spring operated retaining pawl 153 drops into a notch 154 in the disk, and prevents backward rotation of the disk 40 and clutch member.

The clutch gear 132 is continuously driven through a spiral pinion 155 secured to a vertical shaft 156, the upper end of which is connected through bevel gears 157 with a 45 horizontal driving shaft 158. The rear end of the driving shaft 158 carries a driving pulley 159 loosely mounted on the shaft and connected therewith by a clutch 160. The clutch is held normally in engagement by a 50 pivoted latch 161 (Fig. 2) which may be swung up to enable the clutch to be disengaged from the pulley by a rod 162. When the clutch is disengaged the shaft may be turned by hand by a hand wheel 163.

55 The devices for severing and holding the welt comprises a lower welt gripping jaw 164, an upper welt gripping jaw 165, and a welt cutting knife 166 arranged to sever the welt close to the jaws (Figs. 25 to 29). The 60 lower jaw 164 is formed on a lever 167 which is pivoted at 168 on the front end of a slide bar 169, and is provided on its lower end with a roll 170. The upper jaw 165 is formed on a plate 171 which is secured to 65 one side of a lever 172 pivoted at 173 to the slide bar 169, and carrying on its rear end a roll 174 which overlies the roll 170 on the lever 167. The welt engaging face of the upper jaw is grooved and receives a thin plate 175 which is provided with projecting 70 teeth adapted to register with a groove 176 formed in the lower jaw and firmly grip the welt. The jaw carrying levers are connected by a spring 177 which tends to hold the jaws open or in the position indicated in Fig. 28. 75 The jaw carrying levers are operated against the tension of the spring to close the jaws by a slide bar 178 mounted in a groove in the face of the slide bar 169, and held and guided in the groove by plates 179 secured 80 to the rear face of the slide 178 and projecting into undercut grooves formed in the bar 169 (Fig. 10). The front end of the slide bar 178 is provided with oppositely disposed inclines 180 adapted to engage the rolls 170 85 and 174 and force them apart to close the welt gripping jaws. The knife blade 166 is mounted in an undercut groove formed in the inner face of the plate 171, and is operated from the reciprocating slide bar 178. 90 The rear end of the blade carries a projecting stud 181 which is adjustably secured to the blade by a screw 182 passing through a slot in the blade. The stud projects into a vertical slot 183 formed in a plate 184 which 95 is secured to the bar 178 by a screw 185. The plate is held from turning on the bar by a rib 186 which projects into a groove in the face of the bar (Fig. 29). The lever 172 carries an adjustable gage 187 provided with 100 a gage finger 188 arranged to engage the inner edge of the welt and determine the extent to which it enters between the welt gripping jaws. The gripper carrying slide bar 169 is supported in a guide plate 189 secured 105 to the frame of the machine (Fig. 4), and the rear end of the bar is pivoted to a slide 190 so that the bar may swing laterally in the direction of the feed. The bar is held normally in position by a spring 191 engaging the end of the bar beyond its pivot (Fig. 10). The bar is advanced and retracted through the movement of the actuator slide bar 178, and its forward movement is limited by a stop shoulder 192 arranged to be 110 engaged by the front end of the slide 190. The bar 178 is provided with a lateral projection 193 extending through a slot formed in the gripper carrying bar, and a spring 194 is interposed between this projection and 115 the bottom of a recess 195 formed in the gripper carrying bar. This spring acts as a yielding connection between the actuator bar and gripper bar for causing the gripper bar to move forward with the actuator bar 120 until the forward movement of the gripper bar is arrested, when the spring will yield to allow further forward movement of the actuator bar with relation to the gripper bar to close the welt gripping jaws and actu- 125 130

ate the cutter blade. When the actuator bar is retracted, the rear end of the bar strikes the end of the guideway in the gripper carrying bar, after which the further rearward movement of the actuator bar withdraws the gripper bar.

The actuating mechanism of the welt gripping jaws is so constructed that after the jaws have gripped the welt and the welt has been severed, the jaws are withdrawn slightly while retaining their hold upon the welt. This bends or bows the welt between the grippers and the welt guide, so that it is in position to rest snugly against the upper of the shoe at the beginning of the sewing, while the gripping jaws are so positioned that they do not press against the upper. This result is accomplished by partially withdrawing the actuator bar 178 after it has been advanced to advance and actuate the gripper jaws and to advance the cutter blade. When the actuator slide is retracted, the frictional engagement between the slide and the rolls 170 and 174 on the gripper jaws causes the gripper jaws and gripper bar to move back with the actuator slide. This position of the parts is indicated in Figs. 10, 25 and 27. The parts remain in this position until one or more stitches have been formed at the beginning of the next sewing operation, after which the actuator slide 178 is moved to its rearward position to open the gripper jaws and withdraw the gripper carrying slide. When the actuator slide is thus retracted, the gripper carrying bar is held from rearward movement during the first part of the backward movement of the actuator slide by a stop latch 196 which engages a depending lug 197 on the gripper carrying bar. After the actuator slide has moved back sufficiently to free the rolls 170 and 174, so that the gripping jaws disengage the welt, continued rearward movement of the actuator slide carries a cam 198 which is formed on the lower end of the plate 184 over the end of the latch 196, depressing the latch so that it is freed from the lug 197. The gripper carrying bar then moves back with the actuator bar during the remainder of its rearward movement.

The mechanism for operating the actuator bar 178 in the manner above described comprises a lever 199 the end of which carries a block 200 mounted to slide in a transverse slot in the bar (Fig. 10). The lever is pivotally supported on a vertical shaft 201, and is provided with a downwardly projecting arm 202 (Fig. 9), the lower end of which is provided with a spiral gear segment 203 engaging a spiral pinion 204 secured to a horizontal shaft 205 (Figs. 5, 7, and 9 to 15). The shaft 205 also carries a pinion 206 engaged by a gear segment 207 formed on a lever 208. The lever is provided with a radially extending slot 209

which is engaged by a bearing block 210 carried by a crank pin 211 which projects from a disk 212. The crank disk 212 is mounted in the casing 127 and is formed on the end of the shaft 126 heretofore referred to. The crank disk is intermittently turned through a partial revolution at proper intervals by a clutch similar in construction to the clutch for driving the crank disk 105 which has already been described. The clutch gear 213 of this mechanism is continuously driven through a spiral pinion 214 connected with the shaft 156 through pinions 215. The controller sleeve 216 is provided with two stop shoulders 217 adapted to be engaged so by the stop tooth 218 of the controller bar 219. The stop shoulders are so arranged that the crank disk makes approximately one-third of a revolution to open and withdraw the welt gripping jaws at the beginning of the sewing operation, and makes approximately two-thirds of a revolution in advancing and closing the gripper jaws, advancing the cutter blade, and partially withdrawing the gripper jaws at the completion of the sewing operation.

The controller bar 219 is similar in construction to the controller bar 136 already described, and is forced yieldingly toward the controller sleeve by a spring 220. The controller bar is automatically actuated to throw the gripper operating clutch into operation in stopping the machine, and the mechanism for thus automatically throwing the clutch into operation is so timed that it operates shortly after the cam shaft of the machine has been reversed and brought to its final stopping position. This gives the operator sufficient time to draw forward the shoe and bring the welt into proper position to be severed after the thread has been freed from the needle. In the construction shown the mechanism for throwing the gripper operating clutch into operation is actuated by the reversing mechanism as it returns to normal position after having turned the cam shaft back to its final stopping position. This mechanism comprises a lever 221, one arm of which is arranged to engage an adjusting screw 222 carried by a block 223 which is secured in the front end of the controller bar 219 (Fig. 15). The other end of the lever 221 is arranged in position to be engaged by a pawl 224 pivoted to an arm 225 which is secured to a rock shaft 226. The pawl is held in normal position against a stop 227 by a spring 228. The rock shaft 226 also carries an arm 229, the upper end of which is arranged in position to be engaged by a projection 230 formed on a disk 231 which is secured to the side of the segment 96 which carries the reversing pawl. A spring 232 is secured to the arm 229, and tends to rock the shaft 226 in a direction to carry the pawl 224 above the end of the 130

lever 221. The arm 229 is normally held in the position indicated in the drawings by its engagement with the projection 230. When the pawl carrying segment 96 is advanced to turn the cam shaft back into stopping position, the projection 230 moves toward the left in Fig. 6, allowing the arm 229 to swing toward the left so that the shaft 226 is rocked sufficiently to carry the 10 end of the pawl 224 above the end of the lever 221. As the pawl carrying segment completes its return movement, the projection 230 rocks the arm 229 and shaft 226, so that the pawl 224 rocks the lever 221 to 15 withdraw the actuator bar 219 and thus throw the gripper operating clutch into operation. In rocking the lever 221 the end of the pawl disengages itself from the lever so that the lever and controlling bar 219 20 are freed, so that the actuator bar is free to ride against the controller sleeve 216 and disengage the clutch when the succeeding stop shoulder 217 engages the stop tooth on the bar.

25 As before stated, the welt gripping jaws move with the shoe in the direction of the feed during the forming of one or more stitches at the beginning of the sewing operation, and the lateral movement of the 30 gripper carrying bar at this time is utilized to throw the gripper operating clutch into operation to disengage the gripping jaws from the welt and move them to their retracted position. The devices for accomplishing this comprise a cam slide 233 provided with a cam 234 arranged to engage a roll 235 carried by the controller bar 219. The cam slide is connected with the gripper carrying bar by a rod 236, one end of 35 which bears against the side of the bar (Fig. 10), and the other end of which is mounted in a bearing in the cam slide, and bears against an adjusting screw 237. The cam slide is provided with a rack 238 on 40 its upper side which is engaged by a pinion 239 formed on a shaft 240, the outer end of which carries a knurled head 241. A torsional spring 242 acts on the shaft and tends to force the cam slide toward the 45 right in Fig. 11, and thus maintain the rod 236 in engagement with the gripper carrying bar. When the gripper carrying bar is moved in the direction of the feed of the shoe, the cam 234 acts to withdraw 50 the controller bar 219 and thus throw the actuating clutch into operation. As the welt gripper jaws are disengaged from the welt and retracted, the gripper carrying bar is swung back into normal position, so that 55 the cam 234 moves toward the right in Fig. 11, allowing the controller bar 219 to return to position to throw the clutch out of operation after it has made a partial revolution. If desired, the controller bar 60

may be manually withdrawn by turning 65 the knurled head 241 to cause the actuating clutch to disengage and withdraw the welt gripping jaws without starting the machine.

The welt holding gripper is moved in the 70 direction of the feed at the beginning of the sewing operation by mechanism which is actuated from the feed slide of the machine (Figs. 3, 9, 10, and 22 to 24). As shown, the feed slide 243 carries a pivoted bearing 75 block 244 engaging a slot 245 in the upper end of a lever 246, the lower end of which is provided with a gear segment 247 engaging a gear 248 which is secured to the rear end of a shaft 249. A pawl carrying arm 250 is 80 secured to the other end of the shaft, and carries a pivoted pawl 251 which is held in engagement with the teeth of a ratchet wheel 252 by a spring 253. The ratchet wheel is formed on one end of a sleeve 85 mounted to turn on the shaft 249, and provided at its inner end with a pinion 254 which engages a rack 255. The rack is secured to one end of a rod 256, the other end of which bears against the side of the 90 actuator bar 178 (Figs. 10 and 24). The ratchet 252 is engaged by a stop pawl 257, and the engagement of this pawl and the actuating pawl 251 with the ratchet is controlled by a disk 258 mounted on the ratchet 95 sleeve. The disk 258 is provided with recessed portions in which the pawls play when the parts are in the position indicated in the drawings. At the beginning of the sewing operation the actuating pawl 100 251 is oscillated during each reciprocation of the feed slide, and feeds the bar 256 forward during the feeding stroke of the slide, so that the welt holding grippers are moved with the shoe during the 105 feed. When the actuator bar 178 is moved back to open and retract the welt gripping jaws, the disk 258 is rocked to disengage the pawls 251 and 257 from the ratchet 252, so that the rod 256 may be returned to its initial position by a spring 259. The disk is thus rocked through gearing 260 connecting the disk with the front end of a shaft 261, the rear end of which carries a spiral pinion 262 engaging a spiral gear 263 which is 110 secured to the hub of the lever 202 by a screw 264 (Fig. 9). By adjusting the gear 263 on the hub of the lever 202 the position of the disk 258 may be varied to determine the extent to which the ratchet 252 is advanced by the actuating pawl during each 115 feeding movement of the feed slide. The movement imparted to the welt gripping jaws may thus be adjusted in accordance with the length of feed given to the shoe. By adjusting the cam slide 233, which 120 throws into operation the clutch for disengaging and retracting the welt gripping 125

jaws, the number of feeding movements given to the jaws before they are opened and retracted may be varied.

When the shoe is drawn forward by the operator to bring the welt into proper position for the action of the welt gripping and severing devices, the extent to which the welt may be drawn through the welt guide is determined by a welt measuring device, the operation of which is controlled from the treadle of the machine. In the construction shown, the welt leads over a welt guide roll 265 loosely mounted on a shaft 266. A welt measuring arm 267 is pivoted above the roll 265, and is provided at the rear of its pivot with a welt engaging clamp 268 arranged to engage and clamp the welt against the roll. The forward end of the arm carries a roll 269 which engages the upper side of the welt. The arm is also provided with a depending lug 270 adapted to be engaged by a cam 271 secured to the shaft 266. The welt measuring arm is forced in a direction to engage the clamp 268 with the welt, as indicated in Fig. 3, by a spring 272. The shaft 266 is provided with a pinion 273 engaged by a rack formed on a vertically sliding rod 274. The rod is connected by a link 275 with an arm 276 secured to the rock shaft 45 (Fig. 32). When the treadle is depressed in starting the machine, the shaft 266 is rocked through the connections described to bring the high part of the cam 271 against the lug 270, and thus rock the arm 267 in a direction to raise the clamp 268 from the welt, and to depress the roll 269 so that it deflects the welt between the guiding roll and welt guide. When the treadle is released the cam 271 is rocked to bring the low part of the cam into register with the lug 270, so that the spring 272 operates the arm 267 to engage the clamp with the welt, and to raise the roll 269 to give up slack welt between the roll and welt guide. The extent to which the welt may be drawn forward through the welt guide by the operator is determined by the slack given up by the roll 269.

The devices for severing the thread and holding the end of the thread supply consist of a thread holder in the form of a spring finger 277 formed on a plate adjustably secured to an arm 278 and arranged to coöperate with the upper corrugated surface 279 of the arm (Figs. 3, 5, 30 and 31). A cutter blade 280 is secured to the side of the arm 278 in position to sever the thread when it is drawn under the finger 277, as indicated in Fig. 30. The arm 278 is adjustably secured in a socket formed in the end of an arm 281 which is pivoted at 282 and is held in normal position by a spring 283. The retracted position of the thread holding arm is determined by a stop screw 284,

and the forward movement of the arm is determined by a stop screw 285. After the welt has been severed, the operator raises the shoe and draws the thread under the finger 277, thus introducing the thread into the holder and severing the thread from the thread supply. At the beginning of the sewing operation the thread holding arm holds the end of the thread supply under tension, and swings forward against the tension of the spring 283 to give up thread to the thread handling devices during the formation of the first stitch. The arm continues to hold the thread under tension during the sewing until the forward feed of the shoe withdraws the thread from the thread holding finger. This insures the forming of a tight seam at the beginning of the sewing operation.

The welt guide slide 286 is forced yieldingly forward by a spring 287 (Fig. 5), and is retracted by a clutch box 288 (Fig. 8) connected by a yielding link 289 with the actuating lever 290. The slide is locked by a roll 291 and a locking wedge 292 formed on the end of the locking slide 293.

The back rest slide 294 is forced forward by an arm 295 (Figs. 4, 5 and 10) loosely mounted on the shaft 201, and having its hub coupled to the upper end of a sleeve 296, the lower end of which is provided with a pinion 297 engaging teeth formed on a rack slide 298 which is forced in a direction to advance the back rest slide by a spring 299 (Fig. 4). The spring is interposed between the end of the slide 298 and the head of a bolt 300 which passes through the slide and is screwed into an adjusting nut 301.

The means for locking the back rest slide comprises a roll 302 (Figs. 8 and 10) which is interposed between the upper surface of the bar and a locking incline 303 formed on a vertically movable plunger 304. The roll is provided with trunnions which project into slots formed in the plunger and is forced in a direction to unlock the back rest slide by a spring 305. The plunger is supported upon a spring 306 (Fig. 19), and is forced down to bring the incline 303 into locking engagement with the roll 302 by a cam 307 formed on a slide rod 308. The rod 308 is actuated to effect locking and unlocking of the back rest slide by a slide 309 underlying the locking slide 293, and provided on its under side with inclined teeth engaging inclined teeth on the slide 308. The slides 293 and 309 are actuated to lock the back rest slide and welt guide slide through an arm 310 pivoted on the shaft 311 and provided with a lug 312 engaged by a screw 313 carried by an actuating arm 314 which is held against a cam on the cam shaft by a spring 315. The arm

310 is held in engagement with the arm 314 by a spring 316. The lower end of the arm 310 carries a pivoted head 317 which projects on opposite sides of its pivot 318 (Figs. 8, 19 and 20). The upper end of the pivoted head plays between two lugs 319 projecting laterally from the slide 293, while the lower end of the head plays between two similar lugs projecting from the slide 309. When the arm 310 is moved to lock the back rest slide and the back gage slide, the slides 293 and 309 will be moved in unison until the movement of one or the other is arrested and then the pivoted head 317 will rock during the continued movement of the arm 310 until the movement of the other slide is arrested. Both locking devices will therefore be firmly forced into locking position by the spring 316, and the pivoted head will act as an equalizing device to insure the application of an equal pressure to both of the locking devices.

In case it is desired to stop the machine without actuating the reversing mechanism and the mechanism for severing and holding the welt, a stop arm 320 (Figs. 1, 2 and 3), which is pivoted to the lower end of the slide 50, may be swung into position to engage the under side of the machine frame when the treadle is raised and prevent the upward movement of the slide and the throwing into operation of the reversing and welt holding and cutting mechanisms. The adjusting screw 321 in the stop arm 35 may be so adjusted that the stop arm allows the treadle to move upward sufficiently to bring the driving clutch into mid-position between the high and low speed driving points, so that the machine is disconnected 40 from the driving mechanism when the treadle is released. When the treadle is again depressed to start the machine, the stop arm 320 automatically swings into inactive position. The same result may be 45 accomplished by a spring pressed latching pin 322 which is arranged to engage a notch in the rod 50 (Fig. 6).

By the mechanisms above described the machine is automatically reversed to cast 50 off the loop from the needle and bring the parts into position for the removal of the shoe, and the welt is automatically severed and held upon the release of the treadle and without requiring any further manipulation or attention on the part of the operator 55 except to draw the shoe forward so as to draw the welt through the welt guide and into position to be engaged by the welt holding and severing devices as the machine is stopped. In stopping and reversing 60 the machine the slowing down of the machine before the stopping devices are brought into action is insured, so that the forward rotation of the cam shaft is ar-

rested while it is moving at a uniformly 65 slow speed, and the cam shaft is turned back and brought to rest with a gradually retarded motion, so that a uniform stopping of the machine without undue shock or jar, and without wear upon the parts, 70 is insured.

While it is preferred to employ the specific construction and arrangement of parts shown and described in embodying the invention in the machine of the application 75 referred to, it will be understood that this construction and arrangement is not essential, and may be varied and modified as found desirable or best suited to the construction of machine in which the invention 80 is to be embodied, without departing from the broader features of the invention.

The thread cutting and holding devices shown and described form the subject matter of a divisional application, Serial No. 85 769,366, filed May 23, 1913, which resulted in Patent No. 1,187,071, and the stop mechanism shown and described forms the subject matter of a divisional application, Serial No. 246,684, filed July 25, 1918. 90

Having explained the nature and object of the invention, and specifically described one form of machine in which it may be embodied, what I claim is:—

1. A sewing machine, having, in combination, stitch forming mechanism, welt severing and holding devices, and mechanism automatically thrown into operation upon stopping the machine for actuating the devices to sever and hold the welt. 95

2. A sewing machine, having, in combination, stitch forming mechanism, welt severing and holding devices, mechanism for reversing and stopping the machine, and mechanism controlled from the reversing 105 and stopping mechanism for actuating the devices to sever and hold the welt.

3. A sewing machine, having, in combination, stitch forming mechanism, mechanism for stopping the machine with the stitch 110 forming mechanism in a predetermined position, and mechanism acting automatically to sever and hold the welt upon the stopping of the machine.

4. A sewing machine, having, in combination, stitch forming mechanism, mechanism for stopping the machine with the stitch forming mechanism in a predetermined position, welt cutting and holding devices, and mechanism thrown into operation by the 120 stopping mechanism for actuating the welt cutting and holding devices.

5. A sewing machine, having, in combination, stitch forming mechanism, welt cutting and holding devices, mechanism for actuating the devices to sever and hold the welt, mechanism for moving the welt holding devices in the direction of the feed, and mech-

- anism thrown into operation by said movement for withdrawing the welt holding devices.
6. A sewing machine, having, in combination, stitch forming mechanism, welt cutting and holding devices, mechanism for moving the welt holding devices in the direction of the feed, mechanism for freeing and withdrawing the welt holding devices thrown into operation by the movement of the welt holding devices, and means for varying the number of feeding movements required to throw the mechanism into operation.
7. A sewing machine, having, in combination, stitch forming mechanism, a feed slide, welt cutting and holding devices mounted to move with the shoe, a ratchet, and connections for moving the welt holding devices, and an actuating pawl operated from the feed slide.
8. A sewing machine, having, in combination, stitch forming mechanism, a feed slide, welt holding and cutting devices mounted to move with the shoe, a ratchet and connections for moving the welt holding devices, an actuating pawl operated from the feed slide, a stop pawl, mechanism for retracting the welt cutting and holding devices, and means operated from the latter mechanism for disengaging the pawls.
9. A sewing machine, having, in combination, stitch forming mechanism, a welt guide, welt holding grippers, and mechanism for actuating the grippers to engage the welt and then withdraw to bow the welt between the welt guide and grippers.
10. A sewing machine, having, in combination, stitch forming mechanism, a welt guide, welt cutting and holding devices, mechanism for actuating the devices to cut and hold the welt and to bow the welt between the holding devices and the welt guide.
11. A sewing machine, having, in combination, stitch forming mechanism, welt holding jaws, a carrier bar on which the jaws are mounted, a cutter blade, an actuator slide bar for actuating the cutter blade and jaws, a spring between the bars, and a stop for limiting the forward movement of the carrier bar.
12. A sewing machine, having, in combination, stitch forming mechanism, welt holding jaws, a carrier bar on which the jaws are mounted, an actuator bar for closing and opening the jaws mounted to slide in the carrier bar, a spring between the bars, a stop for limiting the forward movement of the carrier bar, a dog for arresting the rearward movement of the carrier bar, and a cam on the actuator bar for rendering the dog inactive.
13. A sewing machine, having, in combination, stitch forming mechanism, a carrier bar, levers pivoted on the carrier bar and

provided with welt gripping jaws, a knife blade mounted to slide in one of the levers, an actuator slide bar arranged to operate the levers and reciprocate the knife blade, and connections for causing the bars to move in unison having provision for movement of the actuator bar relatively to the carrier bar.

14. A sewing machine, having, in combination, stitch forming mechanism, a treadle controlled driving mechanism therefor, a welt guide, a guide over which the welt passes to the welt guide, a welt measuring arm provided with a welt clamp and with a welt deflecting roll, a spring for operating the arm to clamp the welt, a rotary cam concentric with the welt guide for operating the arm to release and deflect the welt, and connections between the cam and treadle.

15. A sewing machine, having, in combination, stitch forming mechanism, a welt severing device, and mechanism automatically thrown into operation upon the stopping of the machine for actuating the device to sever the welt.

16. A sewing machine, having, in combination, stitch forming mechanism, a welt severing device, mechanism for reversing and stopping the machine, and mechanism controlled from the reversing and stopping mechanism for actuating the welt severing device to sever the welt.

17. A sewing machine, having, in combination, stitch forming mechanism, mechanism for stopping the machine with the stitch forming mechanism in a predetermined position, and mechanism acting automatically to sever the welt upon the stopping of the machine.

18. A sewing machine, having, in combination, stitch forming mechanism, mechanism for stopping the machine with the stitch forming mechanism in a predetermined position, welt cutting devices, and mechanism thrown into operation by the stopping mechanism for actuating the welt cutting devices.

19. A sewing machine, having, in combination, stitch forming mechanism, welt gripping devices, mechanism for actuating the devices to grip the welt, mechanism for moving the welt gripping devices in the direction of feed, and mechanism thrown into operation by said movement for disengaging and withdrawing the welt gripping devices.

20. A sewing machine, having, in combination, stitch forming mechanism, a feed slide, welt holding devices mounted to move with the shoe, a ratchet and connections for moving the welt holding devices, and an actuating pawl operated from the feed slide.

21. A sewing machine, having, in combination, stitch forming mechanism, a feed

slide, welt holding devices mounted to move with the shoe, a ratchet and connections for moving the welt holding devices, an actuating pawl operated from the feed slide, a 5 stop pawl, mechanism for retracting the welt holding devices, and means operated from the latter mechanism for disengaging the pawl.

22. A sewing machine, having, in combination, 10 stitch forming mechanism, welt holding jaws, a carrier for the jaws mounted for forward and return movements and for movement in the direction of feed, an actuator slide mounted for movement with the 15 carrier, a spring between the carrier and slide, means for advancing and retracting the slide, and a stop for limiting the forward movement of the slide.

23. A sewing machine, having, in combination, 20 stitch forming mechanism, a carrier bar, levers pivoted on the carrier bar and provided with welt gripping jaws, a knife mounted to slide in one of the levers, an actuator slide arranged to pass between 25 the levers to actuate them, connections between the slide and the knife, connections for causing the slide and carrier to move in unison having provision for movement of the slide relatively to the carrier, and 30 mechanism for advancing and retracting the actuator slide.

24. A sewing machine, having, in combination, stitch forming mechanism, welt holding jaws, a carrier bar on which the 35 jaws are mounted, an actuator bar for opening and closing the jaws, a spring between the bars, means for advancing and retracting the actuator bar, a stop for limiting the forward movement of the carrier bar, a stop 40 for temporarily arresting the rearward movement of the carrier bar when the actuator bar is retracted, and means for rendering the latter stop inactive during the latter part of the rearward movement of 45 the actuator bar.

25. A sewing machine, having, in combination, stitch forming mechanism, welt holding and severing devices, mechanism for automatically withdrawing said devices at 50 the beginning of the sewing, and means for manually controlling the withdrawing mechanism.

26. A sewing machine, having, in combination, 55 stitch forming mechanism, a welt holding device for holding the welt at the completion of the sewing, mechanism for withdrawing the welt holding device, and means for automatically and for manually controlling said withdrawing mechanism.

60 27. A sewing machine, having, in combination, 65 stitch forming mechanism, a welt holding device, mechanism for actuating said device to hold the welt at the completion of the sewing, mechanism for actuating said device to release the welt at the be-

ginning of the sewing, and means for manually controlling said latter mechanism.

28. A machine, having, in combination, mechanism for attaching a welt to a shoe and mechanism for automatically severing 70 the welt at the completion of the welt attaching operation.

29. A sewing machine, having, in combination, mechanism for sewing a welt to a shoe and mechanism for automatically severing 75 the welt at the completion of the sewing.

30. A sewing machine, having, in combination, mechanism for sewing a welt to a shoe and means for automatically severing 80 the welt and holding its free end at the completion of the sewing.

31. A machine, having, in combination, mechanism for attaching a welt to a shoe and mechanism for automatically severing 85 the welt and holding its free end at the completion of the welt attaching operation.

32. A machine, having, in combination, mechanism for attaching a welt to a shoe, mechanism for stopping the machine, and 90 mechanism acting automatically to thereafter sever the welt.

33. A sewing machine, having, in combination, mechanism for sewing a welt to a shoe, mechanism for stopping the machine, 95 and mechanism acting automatically to thereafter sever the welt.

34. A sewing machine, having, in combination, stitch forming mechanism, welt holding jaws, a carrier bar on which the 100 jaws are mounted, an actuator bar for opening and closing the jaws, a connection between the bars for causing them to move together and permitting independent movement of the actuator bar during the last 105 part of its advance and the first part of its return movement, means for advancing and retracting the actuator bar, a stop for limiting the forward movement of the carrier bar, a stop for temporarily arresting the 110 rearward movement of the carrier bar when the actuator bar is retracted, and means for rendering the latter stop inactive during the latter part of the rearward movement of the actuator bar.

115 35. A sewing machine, having, in combination, stitch forming mechanism, welt holding jaws, a carrier bar on which the jaws are mounted, an actuator bar for opening and closing the jaws, a cutter connected 120 with the actuator bar, a connection between the bars for causing them to move together and permitting independent movement of the actuator bar during the last part of its advance and the first part of its return movement, means for advancing and retracting the actuator bar, a stop for limiting the forward movement of the carrier bar, a stop for temporarily arresting the rearward movement of the carrier bar when the 125 130

actuator bar is retracted, and means for rendering the latter stop inactive during the latter part of the rearward movement of the actuator bar.

5. 36. A sewing machine, having, in combination, stitch forming mechanism, welt cutting and gripping devices comprising an actuator bar, a cutter connected with the actuator bar, a gripper bar, welt gripping 10 jaws mounted on the gripper bar, means for

advancing and retracting the actuator bar, and means actuated by the movement of the actuator bar for advancing and retracting the gripper bar and for relatively actuating the welt gripping jaws.

ALBERT LATHAM.
